W. S. JOHNSON ET AL

ELECTRIC RIVET HEATER

Filed March 21, 1921

Wm S. Johnson and
John J. Shaffer
BY

F. H. Gibbs
ATTORNEY

UNITED STATES PATENT OFFICE.

WILLIAM S. JOHNSON AND JOHN W. SHEFFER, OF BERWICK, PENNSYLVANIA,
ASSIGNORS TO AMERICAN CAR AND FOUNDRY COMPANY, OF ST. LOUIS,
MISSOURI, A CORPORATION OF NEW JERSEY.

ELECTRIC RIVET HEATER.

Application filed March 21, 1921. Serial No. 454,036.

To all whom it may concern:

Be it known that we, WILLIAM S. JOHNSON and JOHN W. SHEFFER, residing at Berwick, in the county of Columbia and State 5 of Pennsylvania, and being citizens of the United States, have invented certain new and useful Improvements in an Electric Rivet Heater, of which the following is a full, clear, and exact description, such as 10 will enable others skilled in the art to which it appertains to make and to use the same, reference being had to the accompanying drawings, which illustrate the preferred form of the invention, though it is to be 15 understood that the invention is not limited to the exact details of construction shown and described, as it is obvious that various modifications thereof within the scope of the claims will occur to persons skilled in the 20 art.

In said drawings:

The figure is a perspective view showing our improved electric rivet heater, the protecting hood being shown partly open, and 25 part of the supporting frame being shown in dotted lines.

It is the object of our invention to provide an improved electric rivet heater that is equipped with a protecting hood so that 30 the heater may be used where exposed to the elements without risk of the coil insulation being damaged.

In the drawings, the primary coils 1, secondary coils 2 and separators 3 are supported upon a laminated core confined between the angle bar members 17 that are held against the core by the bolts 18, the bolts 18 serving also to secure the hoisting loops 19 and the U-shaped angle bar supporting member 20 to the member 17. The lower bolt 18 also secures the members 17, 19 and 20 to the core retaining members 7 which are supported on and connected to the side members 4 and 5. Joining the members 4 and 5 is the connecting member 6 which also serves as a guide and a stop for the electrode operating levers 21. Adjustably supported from the U-shaped mem-

ber 20 by the bolts 22 are the upper electrodes or terminals of the secondary coil 2. 50

To protect the heater from the elements when used in an exposed position, a hood is provided comprising sides 8 and 9 of substantially circular shape. The sides have their edges bent inwardly, as at 10, and secured to the sides, close to the edges, are rollers 11, the rollers 11 and the bent portions 10 of the sides retaining the sliding cover sections 12 in position. There are three of these cover sections and they permit of the hood being opened sufficiently to permit of rivets being heated or to a greater extent so that the hoisting loops 19 can be used without necessitating the removal of the hood from the heater. The sections are 65 provided with handles 13 for convenience of operation.

The sides 8 and 9 are joined by the rods 14 and nuts 15 which serve to keep the sides together so as to retain the cover sections 70 in place. Screws 16 engaging the sides 8 and 9 and the core retaining members 17 at the ends of the core serve to secure the hood to the heater frame.

What we claim is:

1. In an electric rivet heater, a frame, coils carried by said frame and a sectional sliding hood for said coils secured to said frame. 75
2. In an electric rivet heater, a frame, coils carried by said frame and adjustably opening covering means for said coils. 80
3. In an electric rivet heater, a secondary coil adapted to receive a rivet for heating and covering means for said coil adapted to 85 open to permit insertion of the rivet.
4. In an electric rivet heater, a frame, a secondary coil carried by said frame, hoisting loops secured to said frame and a cover for said coil adapted to open to permit the 90 use of said chain hooks.
5. In an electric rivet heater, a frame, coils carried by said frame, flanged members secured to said frame and sliding cover sections for said coils carried by said members. 95
6. In an electric rivet heater, a frame,

coils carried by said frame, hoisting loops secured to said frame, flanged members secured to said frame and sliding cover sections for said coils carried by said members,
5 said cover sections being adapted to be positioned to permit use of said hoisting loops.

In witness whereof we have hereunto set our hands in the presence of two witnesses.

WILLIAM S. JOHNSON.
JOHN W. SHEFFER.

Witnesses:

H. F. TRAUGH,
FRED A. HOFFMAN.
